UNITED STATES PATENT OFFICE.

CHARLES OYSTON, OF LITTLE FALLS, NEW YORK.

SYRINGE.

SPECIFICATION forming part of Letters Patent No. 244,652, dated July 19, 1881.

Application filed May 16, 1881. (Model.)

To all whom it may concern:

Be it known that I, CHARLES OYSTON, of Little Falls, in the county of Herkimer and State of New York, have invented certain useful Improvements in Syringes, of which the following is a specification.

This invention is designed as an improvement on the hose-nozzle for which Letters Patent No. 166,803 were issued to me August 17, 1875; and its object is to construct a hose-nozzle whose parts may be adjusted so that spray of any required degree of fineness may be produced, and with less friction than usual.

The invention consists of a nozzle with flaring lip, containing several fixed cross-bars and adjustable basket-like devices and a tapering screw-thimble, by whose adjustment relatively to each other and to the cross-bars the fineness of the spray issuing from the nozzle is regulated.

Figure 1 is a longitudinal sectional elevation of the device on line $x x$, Fig. 2. Fig. 3 is a plan of the reverse of the larger basket-like device. Fig. 4 is a side elevation of the smaller of the basket-like devices. Fig. 5 is a plan of the tapering screw-thimble, holding the parts together. Fig. 6 is a sectional elevation of a portion of the nozzle-shell and its contained parts.

Similar letters of reference indicate corresponding parts.

In the drawings, A represents the cylindrical nozzle-shell, secured on the end of a pipe, A', and provided with an outward-flaring lip, a, at the inner edge of which is an annular shoulder, b, beveled on its inner face, as shown at c.

Rigidly secured within the nozzle-shell A are four cross-bars, B, preferably of oval cross-section, from whose central point of union a screw, C, projects forward in the axis of the nozzle-shell A to the plane of the outer edge of the top thereof, as shown in Fig. 1. Over this screw C is fitted an adjustable basket-like device, D, consisting of an annular hub, d, from which several forward-projecting radial ribs or arms, f, project, supporting on their ends a flattened ring, g, whose outer face is flush with the outer face of the annular shoulder b, and whose edges are beveled, as shown at h i.

Over and upon the screw C, and within the basket-like device D, is fitted a smaller basket-like device, E, consisting of hub k and forward-projecting arms l, supporting a flattened ring, m, whose outer edge is beveled, as shown at n, the face of said ring m being flush with that of the ring g. These devices D E are held in position by means of a tapering screw-thimble, F, that is screwed on the screw C and within the device E, as shown in Fig. 1, with its face flush with the faces of the devices D E, and with its exterior tapering or beveled, as shown at o.

It will be seen that with the parts in position as shown in Fig. 1 concentric annular V-shaped openings are formed between the beveled faces b i and h n, and annular openings also between the outer face, o, of the screw-thimble F and the inner face of the ring of the basket-like device E, through which openings thin annular sheets of water may be forced by the action of the piston G.

The devices D E are designed to be adjusted relatively to the cross-bars B and to each other in such a manner that the arms or ribs f l of the one shall be, if desired, opposite the intermediate spaces between the arms or ribs f l of the other and coincident with the intermediate spaces between the bars B, whereby the liquid issuing from the nozzle A shall be broken into fine spray.

It will be seen that by having the basket-like devices D E adjustable their arms or ribs f l can be arranged in any desired relative position with each other and with the fixed bars B, so that the issuing jets of liquid may be more or less broken up, as may be desired, and by beveling the edges of the concentric rings g m the friction of the escaping fluid is much reduced.

In the drawings, Fig. 1, the nozzle-shell A, 90 tube A', and piston G constitute a syringe, and when the piston G is withdrawn or pulled out to draw water through the nozzle-shell A the basket-like device D operates as a valve and is moved by the suction upward against the shoulder p of the screw C, thereby creating large annular openings between the beveled faces b i and h n for the quick admission of

the liquid, as indicated in Fig. 5, and when the piston G is forced down again the valve basket-like device D closes to its seat, as shown in full lines, Fig. 1, and causes the liquid to be ejected in thin annular sheets.

When the nozzle-shell A is used on a hose the part D will have no play, but will be held against the screw-shoulder *p* and the part E, in proper relation thereto, by the thimble F.

10 I do not confine myself to two basket-like devices in the construction of the improved nozzle, as it is obvious that their number may be increased with advantage for certain purposes without departing from my invention.

15 Having thus described my invention, I claim as new and desire to secure by Letters Patent—

1. A hose-nozzle constructed substantially as herein shown and described, consisting of shell A, having flaring lip *a*, containing cross-bars B, screw C, bevel-edged basket-like devices D E, and tapering screw-thimble F, arranged and operated as set forth.

2. In a hose-nozzle, the combination, with the nozzle-shell A, provided with outward-flaring lip *a* and beveled annular shoulder *b*, 25 and cross-bars B, and screw C, of the adjustable basket-like devices D E, provided with ribs or arms *f l*, respectively, supporting bevel-edged rings *g m*, respectively, and held in place one within the other by beveled thimble F, 30 substantially as herein shown and described, whereby the liquid issuing from the said nozzle is broken into spray, as set forth.

3. In a hose-nozzle, the combination of two or more basket-like devices provided with 35 arm-supported bevel-edged rings, fixed adjustably one within the other, substantially as herein shown and described, whereby annular jets of water and spray may be ejected, as set forth.

CHARLES OYSTON.
